UNITED STATES PATENT OFFICE.

OTTO NEUKIRCH, OF CINCINNATI, OHIO.

STREET-CLEANING MACHINE.

No. 880,392.

Specification of Letters Patent.

Patented Feb. 25, 1908.

Application filed April 20, 1906. Serial No. 312,939.

To all whom it may concern:

Be it known that I, OTTO NEUKIRCH, a citizen of the United States, residing at Cincinnati, in the county of Hamilton and State of Ohio, have invented certain new and useful Improvements in Street-Cleaning Machines, of which the following is a specification.

This invention relates to that class of street cleaning machines in which an endless or continuous sweeping device, consisting of a plurality of brooms mounted upon endless flexible elements is employed to convey the dirt from the surface of the ground over an inclined floor or conveyer bed into a receptacle which may be in the nature of a wagon box or body.

The objects of the invention are to simplify and improve the construction and operation of this class of machines, and with these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention; it being, however, understood that no limitation is necessarily made to the precise structural details therein exhibited, and that changes, alterations and modifications within the scope of the invention may be resorted to when desired.

In the drawings, Figure 1 is a side elevation of a street cleaning machine constructed in accordance with the invention. Fig. 1^a is a detail view, in elevation, of a portion of the rear end of the machine. Fig. 2 is a detail plan view of a portion of the endless broom illustrating the construction of the same. Fig. 3 is a perspective detail view of one of the individual broom members, detached. Fig. 4 is a detail end view of one of the individual broom members. Fig. 5 is a detail plan view showing a discharge spout adapted to be used in connection with the machine.

Corresponding parts in the several figures are denoted by like characters of reference.

The improved machine is mounted for transportation upon the bed A of a suitably constructed truck or vehicle supported upon transporting wheels 1—1.

A suitable frame is mounted upon the bed

A, said frame comprising uprights B—B 55 connected by brace members 2—2.

E represents an inclined floor or conveyer bed, the same being provided with side flanges 3; said floor is supported upon cross bars C—C guided in ways S in the uprights 60 B and the ends of which are fitted in eyes 4 at the lower ends of the rods D—D, the upper extremities of which are screw-threaded, and extended through cap plates 5 which are mounted upon the upper ends of the uprights B—B. The threaded upper ends of the rods D are provided with nuts F having cranks G whereby they may be conveniently turned for the purpose of effecting vertical adjustment of the rods D and of the inclined 70 floor which is supported upon the cross bars carried by said rods. The nuts F have been shown as provided with flanges 6 operating in hooked guides 7 upon the cap plates 5.

The flanges 3 are provided near their upper 75 and lower ends with brackets K and K' having slots L—L' for the passage of set screws 8 whereby said brackets are secured adjustably upon the flanges; the brackets K at the upper ends of the flanges occupying 80 an approximately vertical position while the brackets K' near the lower ends of the flanges are approximately horizontal. These brackets afford bearings for transverse shafts 9 carrying pulleys or band wheels J—J and 85 sprocket wheels O, the latter being disposed adjacent to the pulleys nearest the ends of the shafts. The pulleys J and sprocket wheels O support the endless broom or sweeping member, which is composed of 90 belts a traveling over the pulleys J, and endless chains v traveling over the sprocket wheels O; said chains being provided at intervals with laterally extending clamps or clips d, gripping the adjacent belts which are 95 secured therebetween by means of fastening members such as rivets 10. A plurality of individual brooms, H, having bristles c are provided, said brooms being secured upon the belts a by means of fastening members 100 such as screws 11 that extend through the belts into the heads of the broom. In this manner the endless belts, the endless chains, and the broom members are connected with each other so as to form the endless broom.

The endless broom is driven by means of a sprocket chain N passing from a sprocket wheel 12 that is connected with one of the

transporting wheels 1 over a sprocket wheel M upon the shaft 9 that supports the lower end of the sweeping element, which latter is thus continuously operated when the machine is in motion.

- 5 A suitable receiving wagon W is hitched to or connected with the sweeper, as shown in Fig. 1, for the purpose of receiving the refuse discharged over the upper edge of the pan E.
- 10 When the machine is of unusual width, a discharge spout 15, as shown in Fig. 5 of the drawings, may be suitably connected with the upper end of the inclined floor or conveyer bed.

15 From the foregoing description taken in connection with the drawings annexed, the operation and advantages of this invention will be readily understood. The endless broom will carry the dirt and refuse in an upward direction over the inclined floor and discharge the same into the receptacle W. Vertical adjustment of the sweeping apparatus may be effected by means of the nuts F upon the supporting rods D; slack in the 20 belts and chains of the endless broom may be taken up by proper adjustment of the brackets K—K', thus causing the machine to operate satisfactorily under all circumstances.

25 Having thus described the invention, what 30 is claimed, is:—

- 30 1. In a street sweeping machine a bed mounted upon transporting wheels, uprights rising from said bed and having cap plates at their upper ends, screw-threaded rods operating through said cap plates and having nuts bearing upon the latter and provided with 35 eyes at their lower extremities, cross bars

engaging said eyes and operating in slots in the uprights, a flanged floor or conveyer bed supported upon the cross bars, brackets connected adjustably with said floor near its upper and lower ends, shafts journaled in said brackets, an endless broom supported upon said shafts, and means for transmitting motion to the latter from one of the transporting wheels of the machine.

40 2. In a street sweeping machine a bed mounted upon transporting wheels, uprights rising from said bed and having cap plates at their upper ends, threaded rods extending through said cap plates, crank nuts mounted upon the threaded rods and having flanges, guide hooks upon the cap plates engaging the flanges of the nuts, cross bars supported by the threaded rods, an inclined floor mounted 45 upon the cross bars, an endless broom suitably connected with and supported by the floor, and means for driving the endless broom.

50 3. In a street sweeping machine of the 60 class described an adjustably supported flanged inclined floor, supporting brackets connected therewith, shafts journaled in the brackets and provided with band wheels and sprocket wheels, belts operating upon the 65 band wheels, chains operating upon the sprocket wheels and having clips gripping and connected with the belts, and individual brooms secured upon the belts.
